PROCESS AND APPARATUS FOR
DEWAXING OIL

Harmon F. Fisher, Los Angeles, Calif., assignor to
Union Oil Company of California, Los Angeles,
Calif., a corporation of California

Application October 9, 1933, Serial No. 692,723

10 Claims. (Cl. 204—24)

The present invention relates to the separation of wax from wax-bearing oils, and more particularly pertains to the separation of wax precipitate from a suspension thereof in oil.

In view of the presence of paraffin or of wax in a number of lubricating oil fractions derived from paraffin-base crude oils, asphalt-base crude oils, or mixtures or blends thereof, and since the lubricating value of such paraffin or wax is highly doubtful, in the production of lubricating oils from such petroleum fractions containing paraffin or wax, it has become customary to remove most or a substantial portion of this paraffin or wax from the oil. Such a removal of the wax and/or paraffin is mainly for the purpose of lowering its "pour point" and the temperature at which the oil congeals.

A method has recently been developed for separating the wax which has been precipitated from a wax-containing oil, this method employing electricity for such wax separation. According to this method the wax-containing oil, or any fraction thereof, is first diluted with a light hydrocarbon fraction, such as naphtha, liquid propane, butane, etc., then chilled to the proper temperature at which the wax precipitation takes place, and finally the mixture of oil, diluent and precipitated wax is subjected to an electric field or electric potential to aid the agglomeration and deposition of the wax from this mixture. The treatment of the wax-oil-diluent mixture according to this process causes the wax to deposit on the electrodes. It has been found that the wax particles suspended in an oil and subjected to an electric field appear to be drawn to the electrode having a polarity opposite to that of the particles themselves. Thus, if the wax particles are charged negatively, the deposition occurs on the positive electrodes, while, if the wax is positively charged the electric treatment causes it to deposit on the negative electrodes. However, some wax-bearing oils seem to contain wax particles of both polarities, in which case the above-described electric treatment causes these wax particles to deposit on both the positive and negative electrodes.

In operating according to the above-described method it has been found that the potential gradient of the electric field must be comparatively high. Thus, voltages of from 5,000 to 60,000 volts per inch passed through the oil-wax-diluent solution have been found to be effective in agglomerating and depositing the precipitated wax. Also, it has been found that time is an essential factor in the proper treatment of wax-bearing oils, i. e. it is necessary to maintain such oil within

the electric field for a predetermined and constant period of time to obtain the necessary deposition and agglomeration of the wax particles.

In view of the above-described requirement of using electric fields of high intensity it is necessary to construct the electric treating chamber so that the electric field (i. e. the gap between the positive and negative electrodes) is comparatively small. Obviously, the rate of treatment through such small gaps will be rather low unless a large plurality of such electric fields is provided in the electric treating chamber. Also, the use of a large number of ordinary circular electrodes will necessitate a very large and costly treating chamber.

It is therefore one of the main objects of the present invention to provide a treating chamber having a plurality of positive and negative electrodes in a comparatively small and inexpensive treating chamber.

It is another object of the invention to provide electrodes which take up the minimum of space thereby permitting a larger through-put of oil to be treated.

The depositing of the wax on either or both electrodes of a treating chamber gradually diminishes the space provided for the passage of the mixture of wax and diluted oil, and this space or gap may be finally completely closed by depositing wax. Naturally, such a gradual diminishing of the gap, assuming a constant rate of input of oil to be treated, changes the velocity of the mixture passing therethrough. This change in velocity modifies the above-described time element and causes an insufficient depositing of the wax so that the oil solution removed from such treating chambers still contains considerable quantities of precipitated wax. The presence of such precipitated wax obviously raises the pour point of the final product and decreases the lubricating value of the oil.

It is therefore another object of the present invention to provide for the removal of the wax deposited on the electrodes and thus maintain the gaps between the positive and negative electrodes constant.

The above and other objects may be attained by providing a treating chamber equipped with a plurality of interspaced and alternately live and grounded flat plate electrodes, and by providing some of said electrodes with means for heating them and for melting off any wax deposited thereon. The heating means may be in the form of an electric heating coil and may itself act as the grounded electrode.

Therefore, broadly stated, the invention resides in passing the chilled mixture of oil and wax through an electric field produced by a plurality of inter-leaved, alternately live and grounded flat plate electrodes, thus causing the wax particles to deposit on certain of the thin plate electrodes, and periodically heating the surfaces of the electrodes on which the wax deposits, thus melting the latter and causing it to fall to the bottom of the treating chamber from where it is removed by any suitable means.

The invention further resides in a dewaxing apparatus wherein the electrodes are in the form of thin plates, are spaced away from each other to provide gaps therebetween, and are arranged so that they are alternately live and grounded electrodes.

The invention further resides in providing certain of the electrodes with means for heating the surfaces of these electrodes, and means for passing periodically a current through said heating means to heat the surfaces of the electrodes, thus melting any wax depositing thereon.

More specifically stated, the invention resides in a structure for removing wax from a wax-containing oil, which structure comprises a chamber, a plurality of thin, flat plate electrodes within said chamber and spaced away from each other to provide gaps therebetween, a pipe leading into the chamber to introduce therewith a waxy oil to be treated, baffling means within the chamber to cause the thus introduced oil to pass through the above gaps between the electrodes, means associated with the electrodes and adapted to generate an electric field or potential across said gaps and to cause the wax particles to deposit on certain of said electrodes, a pipe leading out from the chamber and adapted to withdraw therefrom the dewaxed oil, and means associated with the electrodes on which the wax deposition takes place for heating the surfaces of these electrodes periodically to melt and remove therefrom the deposited wax.

In its preferred form the chamber may be provided with a conical bottom which opens into a discharge pipe equipped with a pump, such as a gear pump, to remove the wax thus deposited in the lower portion of the chamber.

The means for the periodical heating of the surfaces of certain of the electrodes may preferably consist of a resistance coil wound around the plate electrode but without contact with the metallic surfaces thereof. However, the heating means themselves may be used as the electrodes on which the wax is caused to deposit. Therefore, the invention may further reside in an electrode structure comprising an insulating frame, a metallic band wound on said frame, means for grounding said metallic band or for connecting it to one pole of a source of electric potential, and electric means associated with said band and adapted to heat the same. The heating means includes a pair of electric conductors connecting the opposite ends of the metallic band with the opposite poles of a source of electric current.

The invention still further resides in providing the electrodes with tensional means to prevent them from buckling. These tensional means may consist of tension springs at the corners of the plates, or may consist of insulating spacers or plugs placed within the aforementioned gaps and against the surfaces of adjacent plate electrodes.

Other objects, advantages and features of the present invention will be more evident especially

by reference to the accompanying drawing, wherein:

Figure 1 is a diagrammatic, sectional elevation taken along the axis of a preferred embodiment of the treater;

Figure 2 is a section through the treater, and along line 2-2 of Figure 1;

Figure 3 is an enlarged view of a part of an electrode provided with a preferred type of heating means;

Figure 4 is a cross section taken substantially along line 4-4 of Figure 3;

Figure 5 is a view of a modified type of electrode provided with tensioning means to prevent the buckling of the electrode;

Figure 6 shows a further modified embodiment of an electrode structure in which a band performs the dual function of being both the electrode and the heating means; and

Figure 7 is a section taken substantially along line 7-7 of Figure 6.

In the form of the invention shown in the drawing, and particularly in Figures 1 and 2, the treater includes an outer shell 10 closed at the top with a cover 11, and provided at its lower end with a conical bottom 12, opening into a wax-discharge pipe 13, equipped with a pump 14, such as a gear pump, to remove from the treater the agglomerated wax settling in the bottom 12. Chamber 10 is provided with a pipe 15 leading therewith and provided within the chamber with a plurality of openings 17. This pipe introduces the waxy oil to be treated.

The space within chamber 10 and above the pipe 15 is divided into two compartments by a baffle plate 18 welded or otherwise rigidly attached to the inner walls of the chamber 10. A rectangular opening 19 is provided in the center of baffle plate 18, the inner edges of which are equipped with vertically aligned walls 20. It is thus obvious that the oil to be treated in chamber 10, and entering therewith through pipe 15, passes upwardly through the rectangular opening 19. This space 19 enclosed by the walls 20 is provided with a plurality of vertically disposed flat plate electrodes 22, 23, which are arranged and installed so that they provide gaps or spaces between each pair of electrodes. The electrodes are also arranged so that adjoining electrodes are of opposite polarity. For this purpose electrodes 22 are attached at their upper ends to bars 25 and 26. These bars are equipped with bosses 27 and 28, respectively, by means of which they are attached to insulators 29 and 30. These latter are in turn attached to the inner walls of chamber 10. Electrodes 22 are connected to one pole of a source of high potential by means of a conductor wire 32 entering into chamber 10 through an insulator 33. The electrodes 23 placed between the electrodes 22 and without contact therewith are held in place by means of bars 35 attached at their ends to the inner walls of chamber 10. These electrodes 23 are grounded through chamber 10 and the ground 36.

Electrodes 23 are also provided with resistance coils 38 wound in series over the respective surfaces of these electrodes, the opposite ends of these resistance coils being connected to conductors 39 and 40. These conductors pass out of the treating chamber 10 through insulators 42 and 43 respectively installed in the sides of the chamber. The conductors 39 and 40 are connectible to the opposite poles of a source of electric current not shown in the drawing. As will be described further below, it is necessary to pre-

vent the contact of the resistance coils 38 with the electrodes 23. For this purpose the upper and lower edges of the electrodes 23 are provided with outwardly projecting insulating strips 44 over which the resistance coils 38 are wound, thus keeping said coils away from the faces of the electrodes 23, and preventing any short-circuiting when a current is passed through the coils.

A pipe 46, perforated at 47 leads from the upper part of chamber 10, and is adapted to withdraw therefrom the dewaxed oil.

In operation, the waxy oil to be treated, with or without a preliminary dilution by a diluent such as a liquefied but normally gaseous hydrocarbon, is first chilled to a temperature at which the wax precipitates out of solution. The thus chilled mixture of oil and wax is then passed through pipe 46 and perforations 47 thereof into the interior of chamber 10. After filling the lower portion of the treater the mixture passes upwardly through the space enclosed by the walls 20 and containing the electrodes 22 and 23. Simultaneously, an electric potential is induced through the gaps separating these electrodes, this potential being produced by connecting conductor 32 to a proper source of electricity. As stated above, the electric potential thus induced through the gaps, through which the waxy oil must pass in its upward movement through the treater, acts on the wax particles in suspension and causes them to be withdrawn and deposited on the electrodes having the potential opposite to that of these particles. The polarity of the electrodes 22 and 23 is therefore selected so that the waxy particles deposit on the grounded electrodes 23. The reason for this will be described below. The thus dewaxed oil, or oil and solvent mixture, then rises into the space above the electrodes and is discharged through pipe 46, after entering thereinto through the perforations 47 in said pipe 46. The rate of introduction of the waxy oil through pipe 46, as well as the rate of discharge of dewaxed oil through pipe 46, are such that there occurs a complete depositing of the waxy particles on the electrodes 23.

As stated above, it is essential to keep the waxy oil to be treated in the treating field for a predetermined period of time to cause the desired deposition of the waxy particles. On the other hand, the deposition of this wax on the electrodes changes the gap between the electrodes. This naturally changes the rate of passage of the waxy oil through the electric field, assuming a constant rate of introduction thereof into the treater. Such an increased rate of travel of the waxy oil obviously results in a smaller degree of dewaxing thus producing an oil of a lesser value. To eliminate this disadvantage it is necessary to remove periodically the wax depositing on the electrodes. For this purpose, an electric current is passed through the resistance coils 38 wound on the electrodes 23 carrying the deposited wax on their surfaces. This electric current heats the resistance coils and melts the deposited wax, the position of the resistance coils with respect to the surfaces of the electrodes 23 and the period of passage of the heating current through these resistance coils 38 being such that the wax is melted only substantially at the surface of the electrodes. Obviously, such a melting reduces the coefficient of friction of the wax and permits the agglomerated and deposited wax to fall down into the conical bottom 12 of the treating chamber from where it is withdrawn through pipe 13 by means of the gear pump 14. It is obvious that

the provision of insulating strips 44 on the upper and lower edges of the electrodes 23 prevents short-circuiting when the current is passed through conductors 39 and 40 to the resistance coils 38. It is also obvious that such heating of the wax deposited on the electrodes 23 must be made periodically and each time only for a period just sufficient to reduce the coefficient of friction to cause the wax to fall down into the conical bottom 12 and not enough to materially heat the liquid.

In view of the fact that it is essential to make the treaters so that they are not too bulky, and since the intensity of the electric field, i. e. its potential, must be comparatively high, it has been found preferable to make the electrodes of comparatively thin flat plates and to space them quite close to each other. Obviously, these thin plate electrodes tend to buckle. Such buckling is undesirable not only because of the change in the gap space between the electrodes, but also in view of the dangers which may be caused by short-circuiting as when two adjoining electrodes come in contact with each other. For this purpose, it may be preferable to place the electrodes in tension, such an arrangement being shown in Figure 5. In this figure the electrode 22', similar to the electrodes 22, is provided at its four corners with arms 50 attached to the inner walls of chamber 10 by means of insulators 51 and tension springs 53, which latter tend to prevent the buckling of the electrodes. Obviously, similar tensioning means may also be provided at intermediate points. Also, instead of using these tensioning means, the buckling may be prevented by the use of insulating spacers or plugs placed between adjoining electrodes.

Instead of using a metallic electrode and a separate heating means such as a resistance coil wound thereon, as shown in particular in Figures 40 3 and 4, it is also possible to use an electrode structure which is constructed so that the coil wound thereon acts both as the electrode for the depositing of the wax particles, and as the heating means or resistance coil for the removal of the thus agglomerated and deposited wax. Such a structure is shown in Figures 6 and 7. In these figures an insulating frame, generally indicated by numeral 60 is held in position within the treater by means of a rod 62 similar to rod 35 of Figures 1-3. This frame carries a metallic coil 63 wound thereon, and held in tension by means of strips 64 and 65 made of an insulating material, and springs 66 and 67. Coil 63 is preferably in the form of a band or a thin metallic ribbon and is grounded so as to act as one of the electrodes, i. e. an electrode similar to electrode 23. The opposite ends of this coil 63 are also connected, as this is shown in Figure 1 in conjunction with resistance coil 38, to the opposite ends of a source of electric current. Obviously, the band acts as an electrode for the deposition of wax thereon when an electric potential is imposed across the gaps between adjacent coil systems acting as the electrodes. The coil 63 also acts as the heating means for the removal of the agglomerated and deposited wax when the opposite ends thereof are connected to a source of electric current.

Instead of passing the oil to be treated upwardly through the treater and between the electrodes, it is obviously possible, and sometimes preferable, to introduce the oil to be treated through pipe 46 and remove the treated oil through pipe 16.

The heating of the electrode surfaces during the periodic removal of the wax deposited on the surfaces of these electrodes is undesirable because of the fact that such heating raises the temperature and causes a part of the wax to go back into solution in the oil. To obviate this disadvantage it may be preferable to reverse momentarily the flow of the oil through the treater, thus cooling the electrode surfaces with the de-waxed treated oil, rather than with the oil still containing the wax precipitate.

It is to be understood that the above disclosures are not to be construed as limiting but merely as descriptive of the generic invention, since many variations may be made by those skilled in the art within the scope of the appended claims.

I claim:

1. A process for dewaxing oil which comprises generating an electric field between electrodes of opposite polarity, passing a wax-containing oil through said field whereby wax is deposited on certain of said electrodes and periodically heating said electrodes upon which wax has been deposited to remove the deposited wax from said electrodes while maintaining a body of wax-containing oil in contact with said electrodes.

2. A process as in claim 1 in which the heating of said electrodes upon which wax has been deposited is sufficient to melt the wax but is insufficient to appreciably heat the body of wax-containing oil.

3. In an apparatus for electrically dewaxing oils, a chamber, a plurality of electrodes disposed within said chamber, means to flow the wax-bearing oil between said electrodes, means to impress an electric potential between adjacent pairs of said electrodes to deposit the wax on certain of said electrodes, and means associated with said electrodes and adapted to heat and remove therefrom the deposited wax.

4. In an apparatus for electrically dewaxing oils, a chamber, a plurality of plate electrodes disposed within said chamber, means to flow the wax-bearing oil between said electrodes, means to impress an electric potential between adjacent pairs of said plate electrodes to deposit the wax on certain of said electrodes, and means associated with said certain electrodes and adapted to heat and remove therefrom the deposited wax.

5. In an apparatus for electrically dewaxing

oils, a chamber, a plurality of plate electrodes positioned within said chamber, means to flow the wax-bearing oil through the chamber and between said electrode plates, means to impress an electric potential between adjacent pairs of said plate electrodes to deposit the wax on certain of said electrodes, and electrical means associated with said certain electrodes and adapted to remove periodically therefrom the wax deposited thereon.

6. A structure according to claim 5, wherein the electrical means for removing the wax depositing on some of the electrodes, includes a resistance coil wound around the electrode and without contact therewith.

7. An apparatus for electrically treating wax-bearing oils comprising a chamber, a baffle plate within said chamber, having an opening therethrough and dividing the chamber into a plurality of compartments, means to flow the oil to be treated through said opening from one compartment to another, a plurality of plate electrodes positioned in the path of said oil and arranged so as to cause the oil to pass through the gaps therebetween, means to impress an electric potential between adjacent pairs of said plate electrodes and to cause the deposition of wax on certain of said electrodes, and heating means to remove the deposits from the surfaces of said certain electrodes.

8. A structure according to claim 7, wherein the heating means comprises a resistance coil actuated by electricity to heat the surfaces of the electrode to remove the wax deposited thereon.

9. In combination, a flat plate electrode adapted for the deposition of wax thereon, projecting insulating strips on said plate electrodes, and a heating coil wound over said strips and electrodes and out of contact with the latter.

10. In a dewaxing structure for wax-bearing oils, an electrode structure adapted for the deposition of wax thereon, comprising an insulating frame, a metallic band coil wound on said frame, means for connecting the coil to a source of electric potential, and means for passing periodically a heat-producing electric current through said coil.

HARMON F. FISHER.
